Specification for Design.

Patented Mar. 7, 1922.

Application filed March 25, 1920. Serial No. 368,751. Term of patent 7 years.

To all whom it may concern:

Be it known that I, EARL M. WITHERELL, a citizen of the United States, residing at Duluth, in the county of St. Louis and State of Minnesota, have invented a new, original, and ornamental Design for Leggings, of which the following is a specification, reference being had to the accompanying drawing, forming part thereof.

Fig. 1 is a perspective view of the legging in use.

Fig. 2 is a side elevation of the foot portion of the legging, and

Fig. 3 is a bottom plan view.

The invention comprises a combination knitted fabric, having a hole therein adjacent its foot portion for the protrusion of the heel of the shoe upon which it is worn and a rubber sole permanently attached thereto.

I claim:

The ornamental design for a legging, as shown.

EARL M. WITHERELL.
